JOHN L. ANDERSON, OF OGDEN, UTAH.

NESTING CAMP HEATER.

1,419,600.

Specification of Letters Patent. Patented June 13, 1922.

Application filed December 18, 1919. Serial No. 345,848.

To all whom it may concern:

Be it known that I, JOHN L. ANDERSON, a citizen of the United States, and a resident of the city of Ogden, the county of Weber, and the State of Utah, have invented a certain new and useful Nesting Camp Heater, of which the following, together with the accompanying drawing, forms a full, clear, and exact specification, which will enable others to make and use the same.

This invention relates to a nesting camp heater, and its principal objects are to provide a heating stove for camp use, which shall, first, be simple and sturdy in construction; second, consist of a minimum of separate parts; third, be easily and quickly "knocked down" for shipment and storage; fourth, have its separate parts so formed that when "knocked down" they may be nested to occupy a minimum of space and not to require boxing or crating for shipment; fifth, be rugged and clean-cut in design, and have no fragile parts nor projections that might be broken off in rough handling; sixth, be truly economical in the cost of manufacture; and seventh, have its design based on a system of duplication of parts, thereby making few patterns necessary and allowing parts which are subject to the greatest deterioration to be interchanged with parts which are subject to the least deterioration, thus equalizing the wear and obtaining the maximum life of the parts.

In construction camps, where contractors are required to furnish heat for bunk houses, tents or other portable or temporary shelters, there exist peculiar conditions which the ordinary types of heating stoves now in the market, signally fail to meet. When considering these conditions, it may be mentioned that all equipment must be continually set up, taken down and moved from place to place, under circumstances, which at the best, are unfavorable to the lasting qualities and to the efficient handling of, the ordinary heating stoves. Another condition is, that contractors find it advantageous to carry in stock at remote points, a very complete line of repair parts for all their equipment, so that it becomes highly desirable to reduce the number of separate parts of which any piece of apparatus may be composed, to as few as possible and to use duplicates of one pattern

in as many different places as possible. Not only does this reduce the capital invested in repair parts themselves, but it also reduces the storage space required, the expense necessary to transport reserve parts from place to place, and the labor required to keep accounts of the parts carried in stock.

To overcome the defects of the ordinary heaters, their multiplicity of separate parts subject to loss and breakage, often in spite of expensive boxing or crating, it becomes extremely important that stoves used under the conditions outlined, should effectually meet the requirements summarized in the above stated series of objects of this invention.

The present heater is preferably made of cast iron and is so designed that the body shall consist of a plurality of separate sections, all identical in general shape and size, the shape being preferably that of a hollow frustum of a cone. As a rule, all the sections may be made from two separate patterns, one, a door section, and the other, a plain section. All the body sections of the heater may be mounted on a base section in the desired order, the uppermost body section being surmounted by a cover section, which latter may be provided with an integral collar for receiving the usual smoke pipe. The various sections may be held together by iron rods extending from the base section through the body sections to, and through the cover section, for the purpose of clamping the individual sections together as one structure.

The features of this invention upon which the protection of Letters Patent is desired, are collectively grouped in the appended claims.

In the drawing,

Fig. 1 represents a front elevation of the stove erected complete, ready for use;

Fig. 2, a vertical section taken on line 2—2 in Fig. 4;

Fig. 3, a vertical section taken on line 3—3 in Fig. 4;

Fig. 4, a top plan view, and

Fig. 5, a vertical center section, showing the principal parts of the stove nested for shipment or storage.

Throughout the different views, similar parts are designated by similar numerals.

Referring to the drawing, 10 represents the base section of the stove, and around

the circumference of the base, in its upper surface, is a rabbeted portion 11, adapted to receive the lower part of the ash-box section 12. Section 12 has the door 13 carried by the lugs 15 and hinged in the pin 14, the lugs forming an integral part of the section 12. At its top, the section 12 has the inwardly projecting flange 16, and carries the superposed fire-bowl section 17, the latter having the downwardly projecting flange 18, which is concentric with the flange 16 of the lower section 12, and is adapted to form a close joint between the two sections 12 and 17. Superposed on the fire-bowl section 17 is the upper middle section 12^a, which is an exact duplicate of the ash-box section 12, and further, superposed on the upper middle section 12^a is the top section 17^a, which is an exact duplicate 20 of the fire-bowl section 17. Superposed on section 17^a is the cover section 19, which has the integral collar 20 for receiving the usual stove pipe (not shown).

By referring particularly to Figs. 2, 3 and 25 5, it will be noticed that the lower parts of sections 12 and 12^a are formed into conical flanges as indicated at 21 and 21^a, respectively, and that these flanges fit snugly over the upper portions of the sections below them. The cover section 19 may have the conical flange 22, which is similar to, and of the same size as, the flanges 21 and 21^a.

The various sections of the stove may be firmly clamped together by the rods 23, which have their lower ends formed into countersink heads 24, the latter having their bearings in the bottom section 10, while the rods extend upwardly through holes in vertical alignment with each other in the various superposed sections. The upper ends of the rods 23 may be fitted with nuts 25. The nuts 25, being located far from the corroding action of the fire, always have their threads in good condition and may be readily removed.

The section 17 forms the fire-bowl of the stove, its lower part being fitted with the grate 26 resting on the abutment 27. Section 12^a is provided with the fire door 13^a; and section 12, which forms the ash-box, is provided with the ash-door 13.

The fire-bowl section 17 is obviously subject to a more severe deterioration from the action of the fire, than any other part of the stove, while the top body section 17^a is obviously subject to a much lesser deterioration. But the section 17 is of the identical form as section 17^a, and interchangeable with it. Therefore, when a certain degree of deterioration in the fire-bowl has been reached, where it can no longer be considered as serviceable for its original purpose, it may be interchanged with the top body section, the latter then forming a practically new fire-bowl, while the former still has a con-

siderable use ahead of it under the less severe exposure to the action of the fire.

The sections 12, 17, 12^a and 17^a, all being conical in form and of the same size, allow them to be nested as illustrated in Fig. 5. In 70 nesting the parts, the cover section 19 is preferably placed lowermost, while the sections 10, 12, 17, 12^a and 17^a are preferably placed in consecutive order as shown, the grate 26 being sandwiched between the sections 12 and 17. The lugs 15, on sections 12 and 12^a, may be so placed that they do not interfere at all with the nesting of the sections. This is clearly shown in Fig. 5. The space 27 (Fig. 5), inside the section 12, 80 may be utilized as a container for the doors 13 and 13^a. When nested, the various sections may be fastened together for shipment, by means of loops of wire (not shown) threaded through the holes 21^c, 10^c, 12^c, 17^c, 85 12^{ac} and 17^{ac}.

Having fully described my invention, what I claim is:

1. In a heater, a base section having a rabbeted upper portion, an ash-box section superposed on the base section, the said ash-box section having a lower portion, conforming to the said rabbeted upper portion, a fire-bowl section adapted to be superposed on the said ash-box section, and having a lower flanged portion adapted to engage the upper flange of the said ash-box section; a circumferential flange projecting outwardly from the upper part of the said fire-bowl section, an upper middle section adapted to be superposed on the said fire-bowl section and having a circumferential downwardly projecting flange, adapted to engage the outwardly projecting flange of the said fire-bowl section; an inwardly projecting circumferential flange at the top of the said upper middle section, a top section adapted to be superposed upon the said upper middle section and having a downwardly projecting flange adapted to engage the inwardly projecting flange of the said upper middle section, an outwardly projecting circumferential flange at the top of the said top section, a cover section having a downwardly projecting circumferential flange adapted to engage the flange at the top of the said top section, and a plurality of rods adapted to extend through from the said bottom section to the said top section for the purpose of holding all the said sections together as 110 one structure.

2. In a heating stove sectionalized for nesting, the combination with a base section and a cover section, of an ash-box section adapted to rest on the said base section, an upper middle section similar to the said ash-box section, a fire-bowl section adapted to rest on the said ash-box section and to allow the said upper middle section to be superposed upon the said fire-bowl section, a top 125

section similar to the fire-bowl section adapted for superposing on the said upper middle section and further adapted to have superposed on itself the said cover section, all the 5 sections being so shaped that they may be "knocked down" and nested as specified.

3. In a heating stove, a base portion, a cover portion, body portions intermediate the said base portion and cover portion and 10 comprising a conically shaped hollow ash-box portion, a conically shaped hollow fire-

bowl portion, an upper middle portion similar to the said ash-box portion, a top portion similar to, and interchangeable with, the said fire-bowl portion, and means for holding the 15 said sections together as a unit structure when erected and for allowing the said sections to be separated for nesting, when required.

In testimony that I claim this invention 20 as my own, I subscribe my name hereto.

JOHN L. ANDERSON.
